UNITED STATES PATENT OFFICE.

FREDERICK HACHMANN, OF ST. PAUL, MINNESOTA, ASSIGNOR OF TWO-THIRDS TO WALTER W. WHITMAN, OF ST. PAUL, MINNESOTA, AND ONE-EIGHTH TO JOHN R. BAILEY, OF MINNEAPOLIS, MINNESOTA.

WRENCH.

No. 910,127.

Specification of Letters Patent. Patented Jan. 19, 1909.

Application filed April 11, 1908. Serial No. 426,536.

To all whom it may concern:

Be it known that I, FREDERICK HACHMANN, a citizen of the United States, residing at St. Paul, in the county of Ramsey and State of Minnesota, have invented certain new and useful Improvements in Wrenches; and I do hereby declare the following to be a full, clear, and exact description of the invention, such as will enable others skilled in the art 10 to which it appertains to make and use the same.

My invention has for its object to provide an improved monkey-wrench, and to this end, it consists of the novel devices and combinations of devices hereinafter described and defined in the claims.

The invention is illustrated in the accompanying drawings, wherein like characters indicate like parts throughout the several 20 views.

Referring to the drawings; Figure 1 is a view in side elevation of my improved monkey-wrench, with some parts broken away and other parts in section. Fig. 2 is a transverse vertical section taken on the line $x^2 x^2$ of Fig. 1; and Fig. 3 is a view corresponding to Fig. 2, but with a so-called set-block shown in a different position.

The numeral 1 indicates a bar having a fixed jaw 2. Two rows of oppositely projecting notches or teeth 3 are formed on the bar 1. A slideable jaw 4 is loosely mounted on the bar 1 for co-operation with the fixed jaw 2, and is provided with a rearwardly extended head portion 5 having a rearwardly extended and inturned stop finger 6, the purpose of which will presently appear. Mounted on the bar 1, between the inturned end of the stop finger 6 and the head 5, for a limited rotary movement, is a set-block 7 provided with internal teeth 8 for co-operation with the teeth 3 on the bar 1. Said set-block 7 is also provided with a segmental slot 9 having an adjusting screw 10 mounted therein and held 45 against endwise movement with respect thereto, by a head 11 and a knurled wheel 12. The forwardly projecting end of said adjusting screw 10 has screw-threaded engagement with the head 5 on the slideable jaw 4.

As is evident, when the set-block 7 is turned into the position indicated in Fig. 3, the said set-block, head and slideable jaw may be slid or moved freely over the bar 1, to secure approximately the desired adjust-

ment of the two jaws with respect to each other. Then, by turning the set-block 7 into the position indicated in Fig. 2, its teeth 8 will be brought into engagement with the teeth 3 on the bar 1, thereby securing said set-block, head and movable jaw against endwise movement; and, then by turning the knurled head 12, the movable jaw 4 may be moved to its final adjustment, the set-block 7 acting as a base of reaction for the adjusting screw 10. The stop finger prevents the set-block and head from becoming separated from each other.

As is evident, the improved monkey-wrench may be very quickly and easily applied to any object desired to be grasped, or removed therefrom. It is simple, strong and of comparatively small cost; and has been found highly efficient for the purpose had in view.

What I claim is:

1. In a wrench of the kind described, the combination with a bar having a fixed jaw and provided with teeth upon one side, of a slideable jaw mounted on said bar, a set block rotatively mounted on the bar and having 80 internal teeth for engagement with the teeth on the bar, and an adjusting screw mounted in the said set block and said slideable jaw, substantially as described.

2. In a wrench of the kind described, the combination with a bar having a fixed jaw and provided with teeth upon one side, of a slideable jaw mounted on said bar, a set-block having internal teeth for engagement with the teeth on said bar and provided with 90 a segmental slot, and an adjusting screw mounted in said slot and having screw-threaded engagement with said slideable jaw, substantially as described.

3. In a wrench of the kind described, the combination with a bar having a fixed jaw and provided with teeth upon one side, a slideable jaw mounted on said bar, a set-block having internal teeth for engagement with the teeth on said bar and provided with a segmental slot, an adjusting screw mounted in said slot and having screw-threaded engagement with said slideable jaw, and a stop 100 for limiting the endwise movement of said set-block with respect to said slideable jaw, substantially as described.

4. In a wrench of the kind described, the combination with a bar having a fixed jaw

and provided with teeth upon one side, of a
slidable jaw mounted on said bar, a set-
block having internal teeth for engagement
with the teeth on said bar and provided with
5 a segmental slot, an adjusting screw mounted
in said slot and having screw-threaded
engagement with said slidable jaw, and a
stop finger carried by said slidable jaw for
limiting the endwise movement of the set-

block with respect to the slidable jaw, sub- 10
stantially as described.

In testimony whereof I affix my signature
in presence of two witnesses.

FREDERICK HACHMANN.
